UNITED STATES PATENT OFFICE.

ALFRED CARLSON AND OSCAR FREDERICK CARLSON, OF REARVILLE, ALBERTA,
CANADA.

WRENCH.

1,412,552.

Specification of Letters Patent. Patented Apr. 11, 1922.

Application filed May 5, 1921. Serial No. 467,020.

To all whom it may concern:

Be it known that we, ALFRED CARLSON and OSCAR F. CARLSON, citizens of the United States, residing at Rearville, in the Province 5 of Alberta and Dominion of Canada, have invented certain new and useful Improvements in Wrenches, of which the following is a specification.

This invention relates to improvements in 10 machine bolt wrenches and one object is to provide such a device adapted for ready access to bolts in positions ordinarily difficult to reach. A further object is to provide a wrench of this type having one jaw that is 15 practically automatic in its operation and that is adapted to "find" the nut of a bolt when the head thereof has been located by the opposite jaw. Adjustments of the automatic jaw are possible to permit the device to be 20 used upon bolts of more than ordinary length, bolts located at an angle with the work, etc.

With the foregoing and other objects in view the invention consists in the combination 25 and arrangement of parts to be herein-after fully described, pointed out in the appended claims and illustrated in the accompanying drawing which forms a part of this application and in which—

30 Fig. 1 is a view of our improved wrench in side elevation, partly in section, illustrating its application, the dotted lines denoting an altered position of the adjustable parts of the wrench.

35 Fig. 2 is a view of the brace showing its connection to the spindle.

Fig. 3 is a fragmentary view of the lower jaw.

40 Like reference characters denote corresponding parts throughout the several views.

The wrench comprises a frame 1 substantially the shape of a carpenter's square inverted with the exception of the bent projection or finger 2 which is formed terminally with the perforation 3a. To the longer side of the frame adjacent its free termination the lower jaw-section 3 of the wrench is pivotally secured by the pin 4, the cooperating jaw-section 5 being partly hollow to receive one end of the section 3 and being formed with an elongated slot 6 in which a pin 7, carried by the jaw-section 3, rides whereby said jaw-sections are adjustable relatively. The jaw-section 3 fits snugly into 55 the section 5 so that ordinarily friction will

hold the sections in an adjusted position, further adjustment being manually effected by the operator sliding the section 5 upon the section 3.

Adjustably secured to one end of the jaw-section 5 by the set screw 8 is the angular end-piece 9 formed at its free end with the socket 10 adapted to releasably receive and frictionally retain the close-fitting cap 11, these caps being made to fit nuts 12 of a variety of shapes, the exterior of the caps being standard, however, for cooperation with the socket 10.

The pivoted end of the jaw-section 3 is formed with the toothed segment in mesh 70 with the toothed end 14 of the jaw 15 which is fulcrumed to the frame 1 upon the pin 16, a portion of that section of the jaw 15 between the pin 16 and the teeth 14 being regularly curved for contact with the periphery 75 of the cam 17 supported by the frame and integral with one end of the lever 18.

The free end of the jaw 15 is twisted and perforated and it is practically co-extensive 80 with the finger 2 and spaced away therefrom by the head 19 arranged upon the spindle 20 that extends through the perforated portions of the members 2, 15, one end of said spindle being formed with a socket adapted to releasably receive and frictionally retain 85 the cap 21, similar to the cap 11, the exterior of this end of the spindle being threaded to receive the retaining collar 22. The spindle beyond the lever 15, with relation to the head 19, is provided with another head 23 and terminates in the lug 24 to which the brace 25 is secured.

The brace 25 serves as a handle to conveniently carry the tool and in use the cap 21 is manually applied to the bolt head 26 to 95 be removed from or tightened upon the work 27. The lever 18 is now manually moved from normal position shown in dotted lines, Fig. 1, to the position shown in full lines. This movement causes the lower jaw, through the operation of the cam 17 upon the jaw 15, to ride upon its pivot from substantially the position shown dotted to the position shown in full lines in engagement with the work 12. The lever 18 and cam 17 now lock the jaws 100 in their relative positions and this position can only be changed by the operator manually moving the lever back to the position shown dotted.

Should the cap 11 carried by the lower jaw 110

- not engage the work when the movement of the jaw 3, 5 toward the jaw 15 takes place the end-piece 9 may be adjusted or the jaw section 5 moved relatively to the section 3. 5 Ordinarily the lower or sectional jaw will automatically grip the work when caused to move in the manner described. The operator now rotates the brace 25 and tightens or loosens the bolt 26. By moving the lever 10 18 to dotted position the sectional jaw is removed from the work and the spindle and connections may then be manually lifted from the work by means of the brace or handle 25.
- 15 What is claimed is:—
1. In a wrench, a frame, a finger integral with said frame, a spindle carried by said finger, a cap for said spindle, a brace connected to said spindle, a toothed jaw fulcrumed to said frame and engaging said spindle, a sectional toothed jaw pivoted to said frame, the teeth of said jaws meshing with each other, a cap carried by said sectional jaw, and a lever fulcrumed to said frame and operatively engaging the first named jaw.
  2. In a wrench, a frame, an extension finger integral with said frame, a spindle carried by said finger, a cap for said spindle,
- a brace connected to said spindle, a toothed 30 jaw fulcrumed to said frame with one end engaging said spindle and spaced away from said finger, a sectional toothed jaw pivoted to said frame, the teeth of said jaws meshing with each other, a cap carried by said 35 sectional jaw, and a cam lever fulcrumed to said frame for operative engagement with the first named jaw.
3. In a wrench, a frame, a spindle supported by said frame, a cap carried by said 40 spindle, a brace connected to said spindle, a jaw fulcrumed to said frame and engaging said spindle, a cam lever carried by said frame and operatively engaging said jaw, a sectional jaw pivoted to said frame and in 45 engagement with the said first named jaw for movement synchronously therewith, and a cap carried by said sectional jaw.

In testimony that we claim the foregoing as our own we have hereto affixed our signatures in the presence of two subscribing witnesses.

ALFRED CARLSON.

OSCAR FREDERICK CARLSON.
